(57) **CLAIM**

The ornamental design for a circular food container, as shown and described.

DESCRIPTION

FIG. 1 is a top perspective view of a circular food container showing my new design with a lid closed;

FIG. 2 is a front view thereof with the lid closed, the opposite rear view with the lid closed being identical;

FIG. 3 is a top view thereof;

FIG. 4 is a bottom view thereof;

FIG. 5 is a top perspective view thereof with the lid separated;

FIG. 6 is a front view thereof with the lid separated; the opposite rear view with the lid separated being identical; and,

FIG. 7 is a cross section view thereof, in the direction of line 7-7 of FIG. 1.
